UNITED STATES PATENT OFFICE.

JOSEPH GUEST, OF PITTSBURG, PENNSYLVANIA, ASSIGNOR OF ONE-HALF TO FERDINAND PROTZMAN, SR., SIDNEY M. YOUNGS, FRED. E. YOUNGS, AND RALPH W. CARROLL, ALL OF SAME PLACE.

ROLLS FOR ROLLING METAL.

SPECIFICATION forming part of Letters Patent No. 400,845, dated April 2, 1889.

Application filed November 23, 1888. Serial No. 291,627. (No model.)

To all whom it may concern:

Be it known that I, JOSEPH GUEST, of Pittsburgh, in the county of Allegheny and State of Pennsylvania, have invented certain new and useful Improvements in Rolling Metals; and I do hereby declare the following to be a full, clear, and exact description of the invention, such as will enable others skilled in the art to which it pertains to make and use it, reference being had to the accompanying drawing, which forms part of this specification.

My invention relates to an improvement in rolling metals; and it consists in the combination of two rolls provided with a suitably-shaped pass which is adapted to separate the web of a T-rail at a point close to the flange, and at the same time to so bend the flange, the head, and web portion of the rail as to adapt each of the two pieces to be readily rolled by one or more passes through the rolls into any desired form or section, all of which will be more fully described hereinafter.

The object of my invention is to provide a pair of rolls for the reworking of railroad-rails into angle-irons, splice-bars, &c., and which both cut a rail into two pieces and at the same time change the shape of both pieces preparatory to being passed again through other grooves in the rolls to convert them into angle-irons or other sections.

The accompanying drawing represents a side elevation of a pair of rolls which embody my invention.

A B represent the two rolls, which are provided at one end with the two passes C D, which are separated from each other by the cutting-edges G and R, for separating the rail longitudinally into two parts. The flanged portion O of the rail passes through the groove 40 or pass C, and at the same time that this flanged portion is being separated from the head or top of the rail it is given a bend, as shown. This is necessary to permit making the cutting-edge R thick enough to give the strength 45 required for shearing the web of the rail close

to the flange. At the same time that the flanged portion of the rail is being bent the head and web portion P is flattened and bent, as shown. This equalizes the draft on the head and web portions of the rail by flowing 55 the metal of the head into and thickening the web at the same time that the web is reduced in width, thus distributing the metal throughout the piece, so as to adapt it to be readily rolled into many merchantable forms, such as 55 angles, splice-bars, curved sections, flats, &c.

The principal feature of my invention is in cutting the web close to the flange and bending and distributing the metal in the head and web portions of the rail. This, while greatly 60 facilitating the further rolling of the metal into angle-irons, splice-bars, &c., which may be done in the ordinary grooves used for the purpose, still it will be evident to those skilled in the art that the metal after going through 65 the first pass or grooves C D is in such shape that it may be readily rolled into almost any desired section.

Having thus described my invention, I claim—

1. The combination of the two rolls provided with the two grooves C D, which are separated from each other by the cutter G, for separating the rails at the top of the flange, the grooves being so shaped that both the 75 flanged and the head and web portions are changed in shape at the same time that the rail is being divided, substantially as shown.

2. The combination of two rolls provided with the two grooves C D, which are separated 80 from each other by the cutter G, and separate grooves for finishing each one of the two parts of the rail, substantially as described.

In testimony whereof I affix my signature in presence of two witnesses.

JOSEPH GUEST.
